TROUSER SUPPORTER

L. D. Cook, Kirkwood, N. Y.

Application May 4, 1949, Serial No. 2,436

Term of patent 14 years

(Cl. D17—8)

To all whom it may concern:

Be it known that I, L. D. Cook, a citizen of the United States, residing at Kirkwood, in the county of Broome and State of New York, have invented a new, original, and ornamental Design for Trouser Supporters, of which the following is a specification, reference being had to the accompanying drawing, forming part hereof, in which:

Fig. 2 is a side elevation of the supporter of Fig. 1;

Fig. 3 is a rear elevation of the supporter of Fig. 1; and

Fig. 4 is a plan view of the supporter of Fig. 1.

I claim:

The ornamental design for a trouser supporter, as shown.

L. D. COOK.
